DESIGN FOR A COMBINED LIPSTICK HOLDER AND CIGARETTE LIGHTER

Albert Monturo, Brooklyn, N. Y.

Application November 9, 1945, Serial No. 123,641

Term of patent 14 years

(Cl. D86—10)

To all whom it may concern:

Be it known that I, Albert Monturo, a citizen of the United States of America, residing in Brooklyn, in the county of Kings and State of New York, have invented a new, original, and ornamental Design for a Combined Lipstick Holder and Cigarette Lighter, of which the following is a specification, reference being had to the accompanying drawing, forming a part thereof, wherein

Fig. 1 is a top plan view of a combined lipstick

holder and cigarette lighter, showing my new design;

Fig. 2 is a side elevational view thereof in closed position; and

Fig. 3 is a side elevational view thereof in exploded position.

I claim:

The ornamental design for a combined lipstick holder and cigarette lighter, as shown.

ALBERT MONTURO.
